UNITED STATES PATENT OFFICE.

ALFRED R. BOLUSS, OF NORWOOD, OHIO, ASSIGNOR OF ONE-HALF TO
WILLIAM T. BOTHWELL, OF JERSEY CITY, NEW JERSEY.

STEAM-ENGINE VALVE.

SPECIFICATION forming part of Letters Patent No. 443,233, dated December 23, 1890.

Application filed July 18, 1890. Serial No. 359,156. (No model.)

To all whom it may concern:

Be it known that I, ALFRED R. BOLUSS, a citizen of the United States, residing at Norwood, in the county of Hamilton and State of Ohio, have invented certain new and useful Improvements in Steam-Engine Valves; and I do declare the following to be a full, clear, and exact description of the invention, such as will enable others skilled in the art to which it appertains to make and use the same.

My invention relates to a combined oscillating and reciprocating valve for steam-engines; and the object of the invention is to provide a simple and automatic valve operated by positive motion and which is adapted to exhaust the steam at one end before it is operated or reciprocated, so as to avoid the steam-pressure at the opposite end of the chest from acting as a cushion to the movements of the valve.

With these and other ends in view my invention consists of a valve capable of both oscillating and reciprocating movements in the valve-chest, in combination with a piston-cylinder, a piston reciprocating therein, and means actuated by said piston for rocking the valve on its axis.

My improved valve is constructed with an annular exhaust-passage extending entirely around the cylindrical valve, and on each side of this exhaust-passage are two receiving-ports for the admission of live steam, one of such ports on each side of the exhaust-passage extending entirely through the valve, so as to align with the supply-ports in the chest and piston-cylinder to admit live steam to such cylinder, while the other port extends longitudinally of the valve to admit steam to the chest, whereby the steam-pressure in one end of the chest is adapted to force the valve endwise, and thus reciprocate the valve to cut off the communication between the transverse port, the steam-chest, and the piston-cylinder. While the valve is receiving steam at one end and admitting steam to the piston-cylinder on one side thereof the steam in the opposite end of the chest and from one side of the piston-cylinder is exhausting through an exhaust-port which is common to both of the ports at the ends of the valve, and steam is thus alternately admitted to opposite ends of the valve-chest and on opposite sides of the

piston in the piston-cylinder, while at the same time the exhaust is taking place, so that the steam-pressure in one end of the chest is very materially reduced, and consequently the steam does not act as a cushion to the movements of the valve.

My invention further consists in the combination of devices and peculiar construction and arrangement of parts, as will be herein-after fully described and claimed.

To enable others to understand my invention, I will now proceed to a detailed description thereof, in connection with the accompanying drawings, in which—

Figure 1 is a sectional view taken longitudinally through a piston-cylinder and a valve constructed in accordance with my invention. Fig. 2 is a sectional view through the valve-chest with the valve omitted, and showing the end of the piston-cylinder in elevation, the parts being on a smaller scale than is represented in Fig. 1. Fig. 3 is a vertical transverse sectional view through the valve on the plane indicated by the line $x-x$ of Fig. 1. Fig. 4 is an enlarged detail perspective view of the valve removed from the steam-chest. Fig. 5 is a detail view of the valve in side elevation and partly broken away to show the exhaust ports and passages in the valve.

Like numerals of reference denote corresponding parts in all the figures of the drawings, referring to which—

85

1 designates the piston-cylinder, and 2 the reciprocating piston-head therein. To one end or head 3 of the piston-cylinder is laterally applied the valve-chest 4 of my improved valve 5, and in the opposite end of the piston-cylinder is an opening 6 for the reciprocation of the piston-rod 7, said opening having a steam-tight packing or gland of any preferred form.

The piston-rod 7 is made hollow, as shown, and within said rod is fitted the valve-rod 8, 95 having a head 9 within the bore of the piston-rod, which head impinges against a nut or collar 9' on the end of the piston-rod. The valve-rod 8 is somewhat shorter than the length or distance of movement of the piston-head, and as the said head reciprocates it operates to reciprocate the valve-rod just before the completion of the stroke of the piston-head, thereby rocking or oscillating the valve-

rod to cut off the steam at one side of the piston-head and admit steam to the opposite side of said piston-head. The free end of the valve-rod is provided with a series of teeth, forming a rack 10, which teeth mesh with a toothed sector 10', formed on the periphery of the cylindrical valve 5. The valve-rod passes through and is guided in an opening 11 in the piston-cylinder and the steam-chest, and the teeth constituting the toothed sector 10' on the valve are of such length as to extend longitudinally of the valve for a greater distance than the endwise reciprocating movement of the valve to prevent the rack of the valve-rod from becoming disengaged from the valve as the latter reciprocates.

The valve is in the form of a cylindrical plug, as indicated in Fig. 4, and it is fitted steam-tight in its seat of corresponding form in the steam-chest, in which it is free to rock or oscillate on its axis when operated by the valve-rod and to reciprocate endwise under the pressure of live steam admitted to the steam-chest.

In lieu of applying my valve-chest to the side or top of the piston-cylinder, I secure the chest to one end or head of the cylinder, and in the opposing walls of the cylinder and steam-chest are formed a plurality of openings arranged in two vertical series, one series of such openings 12 constituting the steam-supply ports from one end of the chest to the piston-cylinder, and also the exhaust-ports on the reverse motion of the valve, while the other series of openings 13 form the live-steam ports from the opposite end of the steam-chest to the piston-cylinder and also the exhaust-ports, such independent series of steam-ports being located on opposite sides of the vertical plane of an exhaust-port 14, located in the middle of the bottom of the steam-chest. (See Fig. 3.)

The oscillating reciprocating valve 5 is formed with a deep wide groove 15 at or near the middle thereof, and which constitutes or forms the exhaust space or chamber in the steam-chest, the valve always occupying such positions in relation to the exhaust-port 14 as to permit the escape of spent-steam from the piston-cylinder and the valve-chest through such exhaust chamber or passage 15 to the exhaust-port 14. On opposite sides of this central exhaust-passage 15 I provide the exhaust-channels 16 16', which are cut in the face of the plug or valve and extend part way round the valve, the position of these channels 16 16' being such that one channel is in line with the port 12 or 13 that is exhausting steam, while the other channel is out of line 60 with the other port, to permit the free passage of spent steam from the piston-cylinder to the exhaust-passage 15 and the port 14.

The teeth constituting the toothed sector 10' on the valve are situated within the annular wide steam-passage 15, below the periphery or surface of the valve, so as to avoid contact with the valve-seat.

The steam-ports 13 extend directly through and open into the piston-cylinder on one side of the head 2 therein, while the other series of steam ports 12 communicate with a steam-passage 17, that extends around the side of the cylinder 1 and opens into the opposite end thereof through the other head, as shown in Fig. 1.

Steam is supplied to the chest through a steam-chamber 18, formed by a hollow cap bolted to the outside of the steam-chest, and between the chest and supply-chamber are four inlet-ports 19 19' and 20 20', two of the ports 19 19' being on one side of the exhaust-port 14 and the other two ports 20 20' on the opposite side of the exhaust-port.

The valve is provided with two transverse ports 21 22 for the passage of live steam from the supply-chamber to the piston-cylinder, and these transverse supply-ports 21 22 are enlarged at the ends where they open through the valve, so as to cause each port 21 or 22 to coincide with all the openings of the series of openings constituting the steam-supply ports 12 and 19 or 13 and 20 between the valve-chest, the piston-cylinder, and the supply-chamber, live steam being conveyed to said chamber through a pipe 23.

The valve is further provided with two longitudinal steam passages or grooves 24 25, which are formed in the face of the valve and extend longitudinally thereof from points near the transverse passages 21 22 to and through the ends of the valve, and these steam passages or grooves 24 25 are arranged out of line with each other longitudinally of the valve and adapted to alternately align or coincide with the steam-ports 19' and 20' to permit steam from the steam-chest to alternately pass through said passages to the ends of the steam-chest, whereby the steam-pressure in one end of the steam-chest acts on the end of the valve to reciprocate the latter, which reciprocation of the valve is effected after the steam has been exhausted from the opposite end of the chest and one side of the piston in the piston-cylinder.

The valve is further provided with exhaust-passages 27 28, which extend through the valve, one end of each passage opening into the middle exhaust-chamber 15 of said valve, while the other end of each passage opens through the face of the valve near the end thereof by a port 29 29', respectively, the exhaust-ports 29 29' in the valve being out of line with each other longitudinally of the valve and adapted to alternately coincide with exhaust grooves or passages 30 31' in the steam-chest to permit the steam in the end of the chest to be exhausted through either of the passages while the exhaust from the piston-cylinder is taking place.

This being the construction of my improved valve, the operation thereof is as follows: Live steam is admitted to the piston-cylinder through the passage 17, the ports 12, and the transverse passage 22 in the plug which aligns

with the ports 19, and while steam is being thus admitted to the piston-cylinder on one side of the head steam is admitted to one end of the valve-chest through the passage 24, which aligns with the port 19'. At the same time steam is exhausted from the piston-cylinder through the ports 13, the passage 16', the exhaust-chamber 15, and the port 14, and from the opposite end of the steam-chest 10 through the passage 30', the port 29', the passage 28 into the exhaust-chamber 15 and the port 14. As the piston-head reciprocates in one direction the valve-rod 8 moves therewith and turns or rocks the valve to throw the 15 ports 22 24 therein cut of line with the ports 19 19', and the steam-pressure in the end of the chest moves the valve endwise or reciprocates the same to bring the port 22 into line with the ports 20 and 13 and the passage 25 into line 20 with the port 20' to admit live steam on the completion of the stroke of the piston-head to the piston-cylinder and opposite end of the steam-chest, which rocking reciprocating movements of the valve causes steam to be exhausted from the end of the chest and side 25 of the piston-cylinder into which steam is first admitted through the passages 30 and 27 in the valve, and the passage 17 and ports 12 into the exhaust-chamber 15 and out 30 through the exhaust-port 14. The operation of the parts is entirely automatic and continuous.

Changes in the form and proportion of parts and details of construction can be made 35 without departing from the spirit or sacrificing the advantages of my invention, and I would therefore have it understood that I reserve the right to make such modifications as fairly fall within the scope of my invention.

Having thus fully described my invention, what I claim as new, and desire to secure by Letters Patent, is—

1. The combination, with a piston-cylinder, of a valve-chest secured to the end of the piston-cylinder and having the inlet-ports, such as 19, 19', 20, and 20', and a single exhaust-port, such as 14, and a valve, such as 5, arranged to alternately align with said inlet-ports and communicating constantly with the 50 single exhaust, substantially as described.

2. The combination, with a piston-cylinder and a piston-head, of a valve-chest having the inlet-ports and a single exhaust-port, a combined rocking and reciprocating valve, such as 5, adapted to alternately communicate with the inlet-ports and remaining in constant communication with the exhaust-port, and a valve-rod operated by the piston-head and connected at all times with the 55 valve to oscillate the same, substantially as described.

3. The combination, with a piston-cylinder and a piston-head, of a valve-chest having the inlet-ports and an exhaust-port, and a 60 valve, such as 5, having a positive rocking or oscillating motion imparted thereto by devices operated by the piston-head and having

an endwise reciprocating movement under the pressure of live steam admitted and exhausted alternately to opposite ends of the 70 valve-chest, substantially as and for the purpose described.

4. The combination, with a piston-cylinder and a piston-head, of a valve-chest having the inlet-ports and an exhaust-port and a single 75 valve, such as 5, capable of a positive endwise movement and a rocking or oscillating motion on its axis, for the purpose described, substantially as set forth.

5. The combination, with a piston-cylinder 80 and a piston-head, of a valve-chest having the inlet-ports and an exhaust-port, a valve, such as 5, provided with a single exhaust chamber or passage, the transverse supply-passages extending through the same, and the 85 longitudinal passages extending to the ends of the valve to admit steam alternately to the ends of the valve-chest, substantially as specified.

6. The combination, with a piston-cylinder 90 and a piston-head, of a valve-chest having a single exhaust 14 and communicating with the piston-cylinder through the ports 12 13 and with the steam-chamber by a plurality of ports 19 19' and 20 20', and a combined rocking 95 and reciprocating valve, such as 5, having the central exhaust-passage, the steam-supply passages extending transversely through the same, and the longitudinal passages adapted to alternately align with the ports 19' and 20' 100 between the valve-chest and steam-chamber, for the purpose described, substantially as set forth.

7. The combination, with a piston-cylinder and a piston-head, of a valve-chest having the 105 single exhaust and communicating with the piston-cylinder by the ports 12 13 and with the steam-chest by the ports 19 20, each of the said ports comprising a series of openings, and a rocking and reciprocating valve, such 110 as 5, having the live-steam passages extending transversely through the same and of such area or size as to communicate with all of the series of openings constituting the two ports by which steam is supplied from the steam-chest 115 through the valve to the piston-cylinder, substantially as described.

8. A cylindrical valve or plug having the annular wide exhaust-groove, the steam-supply passages arranged on opposite sides of 120 said annular groove and extending transversely through the valve, and the longitudinal passages in one face of the valve arranged out of line with each other and extending to and through the ends of the valve, substantially 125 as specified.

9. The combination, with a piston-cylinder and a piston-head, of a valve-chest communicating with the piston-cylinder and the steam-chamber by a plurality of ports and having a 130 single exhaust-port, a cylindrical valve having the annular exhaust-chamber, the transverse steam-passages and the longitudinal exhaust-passages opening at their inner ends

into the exhaust-passage and at their outer through the face of the valve, said exhaust-passages in the valve communicating alternately with passages leading to or near the 5 ends of the valve-chest and arranged out of line with each other, substantially as described, for the purpose set forth.

10. The combination, with a piston-cylinder and a piston-head, of a valve-chest communicating with the cylinder and with the steam-chest by a plurality of ports and having a single exhaust, a cylindrical valve provided with a central exhaust-passage, the toothed sector in said passage, the transverse supply and

longitudinal steam-passages, and the tapered 15 grooves or passages 16 16' in the valve between the exhaust-chamber and the transverse supply-passages, and a valve-rod connected to the piston-head and having a rack geared to the toothed sector of the valve, substantially as described. 20

In testimony whereof I affix my signature in presence of two witnesses.

ALFRED R. BOLUSS.
